(57) **CLAIM**

The ornamental design for a hunting blind, as shown and described.

DESCRIPTION

FIG. 1 is a front perspective view of a hunting blind showing our new design;

FIG. 2 is a left side view thereof;

FIG. 3 is a right side view thereof;

FIG. 4 is a front view thereof;

FIG. 5 is a rear view thereof; and,

FIG. 6 is a rear perspective view thereof.

The features of the hunting blind shown in broken lines form no part of the claimed design.

1 Claim, 6 Drawing Sheets
